Primary Examiner — Prabhakar Deshmukh

(74) Attorney, Agent, or Firm — Michael Best & Friedrich LLP

(57) **CLAIM**

The ornamental design for a wearable player, as shown and described.

DESCRIPTION

FIG. 1 is a front, top, right perspective view of a first embodiment of a wearable player showing my new design;

FIG. 2 is a rear, top, left perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and

FIG. 8 is a bottom plan view thereof.

FIG. 9 is a front, top, right perspective view of a second embodiment of a wearable player showing my new design;

FIG. 10 is a rear, top, left perspective view thereof;

FIG. 11 is a front elevational view thereof;

FIG. 12 is a rear elevational view thereof;

FIG. 13 is a left side elevational view thereof;

FIG. 14 is a right side elevational view thereof;

FIG. 15 is a top plan view thereof; and,

FIG. 16 is a bottom plan view thereof.

Broken lines illustrate unclaimed portions of the wearable player and form no part of the claimed design.

1 Claim, 10 Drawing Sheets
